UNITED STATES PATENT OFFICE

AXEL F. CARLSON, OF CAMBRIDGE, MASSACHUSETTS, ASSIGNOR TO THE REECE BUTTON HOLE MACHINE COMPANY, OF BOSTON, MASSACHUSETTS, A CORPORATION OF MAINE

SEWING MACHINE

Application filed September 24, 1928, Serial No. 307,948. Renewed May 28, 1930.

This invention relates to two-thread sewing machines of that type which are adapted to sew a short seam and then come to rest and which are also provided with means for cutting the under thread close to the work at the end of the sewing operation.

One of the objects of the present invention is to provide a novel means for holding the cut end of the under thread until the next sewing operation has begun, the thread-holding means being constructed so as to hold the under thread in proper position to ensure the correct formation of the first stitch upon the beginning of the next sewing operation.

The invention is herein illustrated as it might be embodied in a machine of the type shown in my co-pending application Serial No. 162,890, filed January 22nd, 1927. The sewing machine illustrated in said application is designed for sewing buttonholes and the devices by which the under thread is manipulated are carried by a turret which is rotatably mounted beneath the work and which has a rotative movement at each end 25 of the buttonhole. The turret in turn is provided with a throat plate having a sewing opening in which the upper needle operates and through which the under thread is led.

In accordance with my present invention the throat plate is provided with a thread-retaining notch so situated that when the turret is rotated at the end of the sewing operation the length of under thread which passes through the sewing opening to the work will be drawn into the notch and thereby held.

The thread-cutting mechanism cuts the under thread between the throat plate and the work and by means of my invention the cut end is thus held in proper position to ensure that it will be properly concatenated with the upper thread during the first stitch-forming operation at the beginning of the next seam.

In order to give an understanding of the invention I have illustrated in the drawings a selected embodiment thereof which will now be described after which the novel features will be pointed out in the appended claims.

Fig. 1 is a fragmentary plan view of a por-

tion of the machine carrying the turret, said view illustrating the turret and under thread cutting mechanism;

Fig. 2 is a somewhat diagrammatic view illustrating the manner in which the under thread is drawn into the thread-receiving notch;

Fig. 3 is a plan view of the throat plate with the under thread retained thereby;

Fig. 4 is a side view of the throat plate.

Inasmuch as the present invention relates simply to the manner of retaining the under thread at the end of the sewing operation I have not thought it necessary to illustrate a complete sewing machine but have only shown a sufficient part of such a machine to enable the invention to be understood.

The sewing machine to which this invention is applied is of the two-thread type, it having an upper needle 1 by which the upper thread 2 is manipulated and it also having under-thread manipulating devices in the form of loopers 3 and 4 and loop spreaders 5 by which the under thread 6 is manipulated.

The under-thread handling mechanism is mounted on a turret 7 which is situated beneath the work support and which is rotated at each end of the buttonhole as usual in buttonhole sewing machines. The turret 7 also carries a throat plate 8 which has a sewing opening 9 therein through which the needle 1 operates and through which the under thread 6 passes as it extends from the under thread mechanism to the work 10.

This turret 7 is rotatably mounted in bearings 11 carried by the frame portion 12 of the sewing machine as usual. In some buttonhole sewing machines the frame 12 which carries the turret and the stitch-forming mechanism is movable back and forth on the bed portion 13 of the machine to which the work 10 is clamped, the to-and-fro motion of the frame 12 carrying the stitching down one side of the buttonhole and back along the other side of the buttonhole.

The machine herein illustrated is provided with thread-cutting mechanism for cutting the under thread beneath the work at the end of the sewing operation and the thread-cut-

ting mechanism illustrated is similar to that shown in my co-pending application Serial No. 162,890. In this sewing machine when the sewing on the buttonhole has been completed and the stitch-forming mechanism has been brought to rest the frame 12 is given a forward movement or a movement toward the bottom of Fig. 1 thereby to shift the parts relatively from buttonhole-sewing position to buttonhole-cutting position. During this movement the throat plate 8 will be carried forwardly of that end 14 of the buttonhole 15 at which the stitching was completed and a length of under thread 6 will be drawn out from the source of supply through the throat plate 8 as shown by the dotted lines 6a in Fig. 2.

In sewing machines of this type the stitch-forming mechanism is frequently so arranged that when it comes to rest there will be a loop 16 of upper thread 2 retained by one of the loopers of the under thread mechanism and hence when the parts are carried from buttonhole stitching to buttonhole-cutting position there will be a length of under thread 6a and also a double length of upper thread 2a extending from the work to the throat plate as shown by dotted lines Fig. 2.

The sewing machine illustrated in the above-mentioned application is provided with pull-down arms 17, 18 which seize the length of threads 2a, 6a and pull them down away from the work from the dotted to the full line position Fig. 2. Said machine is also provided with two cutting elements 19 and 20 which are carried by pivoted arms 21, 22 and which at the proper time are swung from their inoperative position shown in Fig. 1 into thread-cutting relation, thereby cutting the threads 2a, 6a between the throat 8 and the work and close to the work.

The parts thus far described are, or may be, all as shown and described in my above-mentioned co-pending application and hence do not need to be further described herein.

In accordance with my present invention the throat 8 is provided with a thread-retaining notch 23 which has a general L shape, it having the vertical portion 24 extending downwardly from the top of the throat plate and then the lateral or horizontal portion 25. The vertical portion 24 is of a size to freely receive the under thread 6 but the lateral portion 25 is of such a width as to grip the under thread when the latter is drawn into it. This thread-receiving notch 23 is so positioned on the throat plate that when the stitch-forming mechanism comes to rest the vertical portion 24 of the notch will be in alignment with the portion 6a of the under thread 6 which extends from the throat plate to the work and consequently when the thread is acted on by the pull-down arms 17, 18 said thread will be drawn into the vertical portion of the notch.

The horizontal portion 25 of the notch has such a dimension that when the turret is turned at the end of the sewing operation to restore it to its initial position the under thread 6 will be drawn into said horizontal portion and because of the relatively narrow dimension of this horizontal portion 25 the thread 6 will be firmly gripped therein as shown in Fig. 3. Hence when the thread cutters 19 and 20 operate to cut the thread the severed end will be firmly gripped in the portion 25 of the thread-receiving notch. This notch is so positioned that the portion of the thread extending from the notch to the under thread mechanism will be held in proper position to ensure its being concatenated with the upper thread during the first stitch-forming operation at the beginning of the next seam.

I claim:

1. A sewing machine, having in combination, stitch-forming mechanism comprising upper- and under-thread handling devices, a turret on which the under-thread handling devices are mounted, a throat plate carried by the turret and having a sewing opening through which the under thread passes to the work, and means to cut the under thread between the throat plate and the work, said throat plate having a thread-receiving notch which is brought into position to receive the under thread by the turning movement of the turret at the end of the seam.

2. A sewing machine, having in combination, stitch-forming mechanism comprising upper- and under-thread handling devices, a turret on which the under-thread handling devices are mounted, a throat plate carried by the turret and having a sewing opening through which the under thread passes to the work, means to pull off a length of under thread, and means to cut said thread close to the work, said throat plate having a right angular thread-gripping notch into which the under thread is forced by the combined action of the pull-off and the turning movement of the turret.

In testimony whereof, I have signed my name to this specification.

AXEL F. CARLSON.
